UNITED STATES PATENT OFFICE.

HENRI TEISSEIRE, OF PARIS, FRANCE.

BODY OF MOTOR-VEHICLES.

1,184,143.

Specification of Letters Patent. Patented May 23, 1916.

Application filed October 30, 1913. Serial No. 798,261.

To all whom it may concern:

Be it known that I, HENRI TEISSEIRE, a citizen of the Republic of France, residing in Paris, France, have invented certain new and useful Improvements in Bodies of Motor-Vehicles, of which the following is a specification.

The object of this invention is to provide a motor vehicle body which can be closed and opened easily and rapidly, and which, as a distinctive feature, can be completely inclosed on its sides by an improved arrangement of window sashes.

Contrary to the usual custom, the windows according to this invention do not all descend into compartments provided below them, neither are they merely detachable and kept separate in independent casings.

The following description in regard to the accompanying drawing, given by way of example, will explain the characteristics and advantages of this invention.

Figure 1 represents a large torpedo shape model cover. Figs. 2, 3 and 4 are respectively diagrammatic sections on V V, X X and Y Y of Fig. 1. Figs. 5 and 6 are drawn to enlarged scale and are an elevation and vertical section on U U, Fig. 5, of a pair of sliding sashes. Fig. 7 is a modified arrangement applied to a small size body, and Fig. 8 is a diagrammatic section on Z Z of Fig. 7.

In the case of bodies that are long and of a size to allow of emergency seats facing forward, the body is constructed with side housings or casings A for the reception of the window sashes when the body is open or merely closed on top by a hood. The pair of sliding sashes represented in part in Figs. 5 and 6 are constructed of metal, or of wood and metal, or other suitable material. They comprise upper and lower members c each of double U-shape. In one pair of the U recesses, is fixed a sash frame a containing a window b, and in the other pair of U grooves is a sash frame e that can be slid in a way to permit the displacement of its window f from in front of the pane b as indicated in broken lines, Fig. 5. This displacement is limited by a projection or stop g which prevents the frame sliding completely out of its guides. The pairs of sashes being in their casings A and the hood opened out, the operation of closing in the latter is effected on each side thus:—Each pair of sashes is raised vertically out of its casing

by any suitable means, as for instance by strap C, being guided in a groove piece h either fixed to the hood support i or formed on it. This groove is gradually widened at its lower part in known manner, so as to permit the lower member c when pulled right up to be pushed outwardly so that the projection j thereof may be lifted on to the projection k on the casing A so as to retain the member c in raised position. The raised sash frame may at the top engage with a channel shaped member l which may be of a length equal to that of the frame and be provided with a clamping screw or other equivalent device. The members c being thus fixed, the sliding sash e with its window f can be drawn sidewise above the door D. The front upright of the sash frame e engages in a groove n fixed to the front screen o. Clamping screws or catches p keep it in position. The sides of the body between the first rib of the roof and the front screen is thus closed in. The windows b and f when in their raised positions engage with their upper edge under the top of the hood which prevents water entering. The rear side portions of the body between the first and second uprights for the roof is closed in in the same manner as the front part. The roof part may be of any construction, provided that the sliding windows can be made use of and be retained in raised position.

In the small type of body shown in Fig. 7, the arrangement differs from the preceding only as regards the rear portion. The front portion between the front screen and the first roof upright is closed in as in Fig. 1. In the rear portion behind the driver's seat is arranged a casing q which stretches across the whole vacant width of the body. In this casing are two windows r fixed in rising and falling sash frames s, each occupying half of the casing q.

To close the side part above the back door D, a window r, indicated in broken lines in Fig. 8, is raised while being guided from the casing q to swinging holder u which is hinged to the roof support i by hinge x. When the window r has been raised completely out of its casing, it is then clamped in holder u by screw y, whereupon the latter may be turned on its hinge x so as to bring the sash over door D so that it occupies the position shown in full lines in Fig. 8, and can be fixed against a vertical strip

α' , attached to the back roof support v , by a pivoted latch z and screw or other suitable retaining means. As the sash s may have a length equal to half the cross casing q it can be adapted to shut a bay in the side of the body greater than the usual width of the door, as shown in Fig. 7.

Having thus described my invention and the best means I know of carrying the same into practical effect, I claim:

- 16 1. A motor vehicle body having a lateral casing adjacent to each doorway for the reception of a frame, a frame adapted to receive a pair of windows and to be lowered into said casing and raised therefrom, whereby said windows may be raised and lowered together, one of said windows adapted to be drawn aside to close an adjacent opening upon said frame being raised 15 out of said casing, the said windows being retained within grooves or guideways attached to the supports of the roof or front screen of the vehicle by clamping or latching devices.
- 20 2. A motor vehicle body having means for closing the rear side portions of the body consisting of a casing arranged transversely of the vehicle behind the driver's seat, a window normally disposed in said casing, a holder pivotally secured to the roof support and adapted to receive the window when the latter is raised out of said casing, and means for securing the window in said holder adapted to release the window therefrom when desired, said holder adapted to be turned so as to cause the window to occupy a position in the side of the body resting against another roof support and retaining devices for securing said window in 25 said side position.
- 30 3. A vehicle body, having a casing for

the reception of a frame, a frame adapted to contain a plurality of windows and having upper and lower grooves to permit a window to be slid into or out of the frame, and means for lowering said frame into said casing and raising the same therefrom.

4. A motor vehicle body having a lateral casing adjacent to each doorway for the reception of a frame, a frame adapted to receive a pair of windows and to be lowered into said casing and raised therefrom, whereby said windows may be raised and lowered together, one of said windows adapted to be drawn aside to close an adjacent opening upon said frame being raised out of said casing, the said windows being retained within grooves or guideways attached to the supports of the roof or front screen of the vehicle by clamping or latching devices, and said motor vehicle body having means for closing the rear side portions of the body consisting of a casing arranged transversely of the vehicle behind the driver's seat, a window normally disposed in said casing, a holder pivotally secured to the roof support and adapted to receive the window when the latter is raised out of said casing, said holder adapted to be turned so as to cause the window to occupy a position in the side of the body resting against another roof support and retaining devices for securing said last mentioned window in position.

In witness whereof, I have hereunto signed my name in the presence of two subscribing witnesses.

HENRI TEISSEIRE.
